UNITED STATES PATENT OFFICE.

GEORGE G. FLOYD, OF CHICAGO, ILLINOIS, ASSIGNOR TO AMERICAN STEEL FOUNDRIES,
OF CHICAGO, ILLINOIS, A CORPORATION OF NEW JERSEY.

TRUCK SIDE FRAME.

1,378,848.

Specification of Letters Patent. Patented May 24, 1921.

Application filed March 4, 1920. Serial No. 363,118.

To all whom it may concern:

Be it known that I, GEORGE G. FLOYD, a citizen of the United States, residing at Chicago, in the county of Cook and State of Illinois, have invented certain new and useful Improvements in Truck Side Frames, of which the following is a specification.

This invention relates to cast metal truck side frames.

10 In my copending application, Serial No. 344,769, filed December 15, 1919, I have set forth at great length the causes and effects of compression, tension and bending stresses set up in a cast metal frame, and which are 15 peculiar to the cast type of side frame. In such case, I disclosed a cast metal side frame having pedestal jaws for receiving separate journal boxes.

This present application relates more 20 specifically to a cast metal truck side frame in which the journal boxes are formed integrally with the side frame. Otherwise, the conditions are the same in both cases. No repetition will be made in this application 25 of the subject matter claimed in said copending application, and only such points as are necessary to give a complete understanding of this present invention will be considered.

30 The object of this invention is to provide a cast metal truck side frame in which the tendency for the integrally formed boxes to swing downwardly and longitudinally inwardly is substantially overcome.

35 This and other objects are accomplished by means of the arrangement disclosed on the accompanying sheet of drawings, in which—

Figure 1 is a fragmentary side elevation 40 of my improved truck side frame, some of the parts being in section;

Fig. 2 is a fragmentary top plan view of the same;

Fig. 3 is an end view of the same side 45 frame; and

Fig. 4 is a side elevation, somewhat diagrammatic in form, of a well known type of truck side frame, in which the journal boxes form integral parts of the side frame.

50 The various novel features of the invention will be apparent from the following description and drawings, and will be particularly pointed out in the appended claims.

55 Attention is directed first to Fig. 4 of the

drawings, wherein it will be noted that I have shown a truck side frame 10, having a tension member 11, compression member 12, columns 13, and journal boxes 14, cast integrally in a single piece. It will be noted 60 that the tension and compression members 11 and 12 are not connected directly to each other at their outer ends, but are connected by a metal portion 15, which lies just inwardly from the inner side of the journal 65 box 14. From this figure it is apparent that if the tension and compression members were projected in straight lines outwardly, they would meet at a point substantially in the middle of the journal box; in other 70 words, at a point in space.

Under these conditions, it is apparent 75 that if the truck side frame is loaded in the usual manner, a compressive force will act outwardly in the direction of the arrow C, and a tension force will act inwardly in the direction of the arrow T. As a result of these two forces acting in different directions, which are substantially opposite to each other, a longitudinal shearing action is 80 set up in the line S—S of metal section 15.

A further effect, and probably more serious one, is the actual swinging effect given to the journal boxes, this swinging action being downwardly and longitudinally inwardly. To overcome in part this swinging effect of the integrally formed journal boxes, a reinforcing fin 16 is formed on the compression member and extended over the journal box 14. In actual operation, it was 90 found that while the reinforcing fin 16 may have been of some value, fractures appeared in the reinforcing fin 16 over the journal boxes 14 and slightly inwardly therefrom, resulting in a further bending or swinging 95 action of the journal boxes in the manner hereinabove mentioned. In many cases the fractures extended to such degree that the side frames failed.

This problem is one which is peculiar to 100 the cast type of side frame having the integrally formed journal boxes, and it is to overcome this objectionable feature that I have designed the side frame disclosed in Figs. 1, 2 and 3 of the drawings.

105 Referring now to these figures, it will be noted that the cast metal side frame includes a tension member 17, compression member 18, columns 19 (only one of which is shown) and journal boxes 20 (only one of which is 110

shown), all cast in a single piece. Preferably, the tension and compression members are of channel section, with their webs 21 and 22 located at the upper side of each of said members respectively.

It will be noted that these web members 21 and 22 are joined directly to each other at the point 23, which is vertically over the middle of the journal box 20. In this way, 10 the compression stresses in the compression member 18, and tension stresses in the tension member 21, do not act to swing the integrally formed journal boxes 20 downwardly and longitudinally inwardly. The 15 web members 21 and 22 outwardly from the columns 19 extend in straight lines and carry the compression and tension stresses primarily along said lines.

As set forth in my said copending application, 20 the web portion 21 of the tension member is located at the upper side of the tension member to overcome certain high bending and tension stresses which are peculiar to the cast metal type of side frame. 25 By means of this same arrangement, and connecting the tension and compression members in the manner shown with respect to each other, and with respect to the integrally formed journal boxes, I have overcome the tendency for the journal boxes to 30 swing downwardly and longitudinally inwardly. By means of this arrangement, any shearing action or fracturing action above and to the sides of the journal boxes 35 is overcome. It will be noted that the main tension stresses transmitted through the tension member 17 are transmitted directly to the compression member and are not passed through the journal box structure 40 proper.

By means of the combination of parts hereinabove described, the tendency of the box to revolve on the journal is eliminated, the point of connection between the compression and tension members being approximately over the middle of the journal box or point of support.

It is my intention to cover all modifications of the invention as set forth in the following claims.

I claim:

1. A truck side frame including tension and compression members and journal boxes all cast in a single piece, the tension and compression members being of channel section with the webs thereof at the upper side of each of said members respectively, and being joined directly to each other over the middle of the journal box to prevent downwardly and longitudinally inwardly swinging movement of the journal boxes.

2. A truck side frame including tension and compression members and journal boxes all cast in a single piece, the tension member being of channel section and having its web at the upper side thereof, and joined directly to the compression member over the middle of the journal box to prevent tendency of the journal box to revolve.

3. A truck side frame including tension and compression members and entire journal boxes all cast in a single piece, said tension and compression members being directly connected to each other over the journal box to prevent tendency of said journal box to revolve.

Signed at Chicago, Illinois, this 28th day of February, 1920.

GEORGE G. FLOYD.
